US00D735093S

(12) **United States Design Patent**
Morrish et al.

(10) **Patent No.:** **US D735,093 S**
(45) **Date of Patent:** **** Jul. 28, 2015**

(54) **EVACUATION CHAIR**

(71) Applicants: **Gerald David Morrish**, Hertfordshire (GB); **Kenneth George Morrish**, Hertfordshire (GB)

(72) Inventors: **Gerald David Morrish**, Hertfordshire (GB); **Kenneth George Morrish**, Hertfordshire (GB)

(**) Term: **14 Years**

(21) Appl. No.: **29/469,649**

(22) Filed: **Oct. 11, 2013**

(30) **Foreign Application Priority Data**

Apr. 15, 2013 (EM) 002220426-0001

(57) **CLAIM**

The ornamental design for an evacuation chair, as shown and described.

DESCRIPTION

FIG. 1 is a perspective view of an evacuation chair showing our new design in a closed position;

FIG. 2 is a rear view thereof;

FIG. 3 is a perspective view thereof, showing the evacuation chair in an open position;

FIG. 4 is a front view thereof;

FIG. 5 is a rear view thereof;

FIG. 6 is a side view thereof, the opposite side being a mirror image thereof; and,

FIG. 7 is a rear perspective view thereof.

1 Claim, 7 Drawing Sheets
